[57] CLAIM

The ornamental design for Christmas tree stand, as
shown as described.

DESCRIPTION

FIG. 1 is a perspective view of a Christmas tree stand
showing my new design, the artificial Christmas tree
shown in broken lines for illustrative purposes only;
FIG. 2 is an enlarged top plan view thereof;
FIG. 3 is an enlarged side elevational view thereof; and,
FIG. 4 is an enlarged bottom plan view thereof.

FIG. 1

FIG. 2

FIG. 3

FIG. 4
